UNITED STATES PATENT OFFICE.

ELDRIDGE H. HORTON, OF CHICAGO, ILLINOIS.

EXPANSION PLUG.

Application filed April 13, 1925. Serial No. 22,751.

This invention relates to new and useful improvements in plugs, and particularly to plugs used in walls and floors for the purpose of attaching trim, and the like, thereto.

5 One object of the invention is to provide a plug which is constructed and arranged to be expanded, within a wall or floor, and beyond the inner face thereof, whereby to securely anchor the plug against being 10 pulled outwardly therefrom, and for providing a means into which to drive fastening devices.

Another object is to provide a plug of this character which includes two parts, 15 one of which is adapted to be driven into the plaster and tile of a wall or floor, and the other of which is adapted to be driven into the first part whereby to expand the said first part, and particularly the portion 20 which extends beyond the inner face of the tile, so that both of the parts will be positively held against displacement, and thus provide an efficient means for nails, or the like, used in attaching wooden elements 25 to the wall or floor.

Other objects and advantages will be apparent from the following description when taken in connection with the accompanying drawing.

30 In the drawing:—

Figure 1 is an elevation of the outer plug portion of the device driven into the plaster and tile of a wall, and the inner plug portion about to be driven into the outer plug 35 portion, the plaster and tile being in section.

Figure 2 is a vertical longitudinal sectional view through the device, the inner plug portion being in the act of entering 40 the outer plug portion.

Figure 3 is an elevation of the device within the wall, with the outer portion expanded by the inner portion of the plug.

45 Figure 4 is a view similar to that of Figure 3, but showing the outer ends of the plug portions cut off flush with the face of the wall, a strip secured thereto.

Referring particularly to the accompanying drawing, 10 represents a portion of the 50 tile of a wall, and 11 the plaster facing thereon, in connection with which the present invention is particularly adapted for use.

The plug includes the two parts 12 and 55 13, the former of which comprises a cylindrical shank portion 14, one end of which

is tapered, as shown at 15, while the other end flares outwardly, as at 16, and is joined to an angular enlarged head portion 17. Within this cylindrical portion there is 60 formed a correspondingly formed bore portion 18, one end of which tapers at 18', similar to the outer tapered end of the shank, while the other portion of the bore, or that portion which extends from the other 65 end of the cylindrical portion to the outer end of the angular head, flares outwardly, as shown at 19. This portion of the device is adapted to be driven into a previously 70 punched or bored opening in the plaster and tile, whereby the jagged wall of said opening will embed itself in the exterior surface of the said portion, by reason of the fact that said plug portion is preferably formed of comparatively soft wood. This portion 75 of the plug may be driven into the opening in the wall to the required distance for the purpose desired.

The inner portion 13, of the device is 80 a solid wooden plug or pin, and has its external face formed in correspondence with the bore of the part 12. This pin 13 is adapted to be driven into the portion 12, with the result that the said portion will be expanded, and split, as clearly shown in 85 Figures 3 and 4, of the drawing, it being noted that the extreme inner end of the portion 12, or that portion which projects beyond the inner face of the tile, spreads out to such an extent that the plug will be 90 effectively held against removal, or any tendency to become loose.

After the pin or plug portion 13 has 95 been driven into the portion 12, so that the latter is properly expanded within the wall, the portions of the plug which project beyond the outer face of the wall are sawed, or cut off so that their outer faces are in the plane of the face of the wall. Trim, or the like is then secured to the 100 wall by nails driven through the trim and into the outer end of the inner plug portion 13, with the result that the nails will be firmly held, and the trim supported against any tendency toward looseness.

If desired, nails may be driven into the 105 two parts of the plug, obliquely, thereby serving to more effectively tie the two parts together, and thus prevent the inner plug portion being withdrawn from the other 110 portion.

Figure 4 shows a molding strip 20 set

cured to the plug by means of the nails 21.

The shoulder 22, formed at the inner end of the angular part 17, serves to compress the plaster into which the device is driven, 5 and also prevents further inward movement of the part 12, when the part 13 is being driven thereinto.

What is claimed is:—

1. An expansible plug comprising a 10 frangible hollow external portion having a bore therethrough the intermediate portion of which is cylindrical while the opposite ends are tapered outwardly and flared outwardly, respectively, said external portion 15 being adapted to be driven into an opening previously made in a wall, and an internal expanding portion having its exterior formed in correspondence with said bore, said flared end being of such a length as 20 to prevent fracturing of the hollow portion until the plug has passed thereinto for a considerable distance, the outer ends of said external and internal portions being arranged to be cut off in the plane of a 25 wall whereby the outer end of the internal portion forms a seat for a molding or the like fastening device.
2. A device for a stone, cement, or the like wall, adapted to receive the fastenings 30 of moldings, baseboards, or the like comprising a readily fractured hollow external

portion adapted to be driven into a previously made opening in a wall and having a tapered shank provided with an angular portion on its larger end adapted to embed 35 itself in the face of a wall, and a solid tapered portion arranged to be driven into the hollow portion to expand and fracture the latter whereby to anchor the latter within said wall opening, said solid portion 40 frictionally holding itself within the hollow portion, the outer ends of the internal and external portions being adapted to be cut off in the plane of the face of the wall whereby said inner portion will form a seat 45 for a nail or screw fastening of a molding, or the like.

3. The combination with a frangible plug having a bore therethrough the intermediate portion of which is cylindrical while the opposite ends are tapered outwardly and flared outwardly, respectively, of an expanding plug having its exterior formed in correspondence with the said bore and arranged to fracture the opposite ends of said 55 frangible plug, said expanding plug being arranged to remain with its intermediate portion frictionally engaged within the corresponding portion of the frangible plug.

In testimony whereof, I affix my signature. 60

ELDRIDGE H. HORTON.
